JOSEPH W. ROGERS, OF WOODBURY, NEW JERSEY.

AUTOMATIC SIGNALING MECHANISM.

1,041,168.

Specification of Letters Patent.

Patented Oct. 15, 1912.

Application filed March 12, 1910. Serial No. 548,810.

To all whom it may concern:

Be it known that I, JOSEPH W. ROGERS, a citizen of the United States, residing at Woodbury, in the county of Gloucester, State of New Jersey, have invented an Automatic Signaling Mechanism, of which the following is a specification.

This invention is an automatic signaling mechanism designed primarily for railway crossings, particularly for use with trains operating in both directions on a track.

The apparatus comprises two starting relays located respectively on opposite sides of the crossing and a signal relay located at the crossing.

The desired result effected by my invention is the automatic operation of a signal by a train as it approaches the crossing from either direction and the automatic discontinuance of the signaling operation after the train has reached a desired point or after the lapse of a desired period.

The characteristic construction and functions of the invention are fully disclosed in the following description and the accompanying drawings in illustration thereof.

In the drawings, Figure 1 is a diagrammatic representation of my improvements; and Fig. 2 is a diagrammatic representation of a modified construction for cutting out the signal.

The invention as illustrated in Fig. 1 is applied to a track comprising the conducting sections A, A' and A² insulated by non-conducting sections A³, A⁴, A⁵ and A⁶.

A rail of the section A is divided by insulation a into sections a² and a³ and a rail of the section A² is divided by insulation a⁴ into sections a⁵ and a⁶. The section A is provided with a starting relay comprising a battery B connected by a conductor b with the rail a⁷, and by the conductor c with a contact point d, the conductor c containing the electro-magnet e. A conductor f connects the conductor c with the rail section a³ and contains the electro-magnet g. A conductor h is tapped onto the conductor f and is provided with the contact point i. A conductor j connects the rail section a² with an armature k adapted to oscillate between the contacts d and i, means such as a spring m serving to hold the armature k in engagement with the contact d normally. On the opposite side of the crossing is the second starting relay comprising the battery B', the

conductor b' connecting it with the rail section a⁸ and the conductor c' connecting it with the contact point d', the conductor c' containing the electro-magnet e'. A conductor f' connects the wire c' with the rail section a⁹ and contains the electro-magnet g'. A conductor h' connects the conductor f' with the contact point i'. A conductor j' connects the rail section a⁸ with an armature k' which is adapted to oscillate between the contacts d' and i', means such as a coiled spring m' being provided to hold this armature in engagement with the contact d' normally.

The electro-magnet e is adapted for attracting an armature n to effect its engagement with the contact point o, the armature being held normally out of engagement with the electro-magnet and contact point by suitable means as a spring p. A conductor q connects the armature n with a conductor R and a conductor s connects the contact point o with a conductor T.

The electro-magnet e' is adapted for attracting the armature n' and effecting its engagement with the contact point o', the armature being held normally out of engagement with the electro-magnet and contact point by the spring p'. The armature is connected by the conductor q' with the conductor R and the contact point o' is connected by the conductor s' with the conductor T.

The crossing relay comprises the battery B² connected by the conductor b² with the conductor T and by the conductor c² with the conductor R, the conductor c² containing the electro-magnet e². A conductor d² connects the conductor b² through a coiled spring d³ with an armature f² adapted to be attracted by the electro-magnet e² against the action of a spring d³ which normally withdraws it from the electro-magnet.

A contact point g² is connected through the resistance coil h² with the conductor c² on one side of the electro-magnet e² and a contact point i² is connected through the bell J with the conductor c² on the other side of this electro-magnet, these contact points being engaged by the armature f² when the latter is attracted by the electro-magnet e². The resistance is used to prevent short circuiting the battery and to reduce the potential across the terminals of the magnet corresponding thereto. Conductors u and v

u' connect the terminals of the electro-magnet e^2 with the respective rails a^9 and a^{11} of the section A'.

In operation, with a train moving in the direction of the arrow, when it reaches the track section A a circuit of the battery B is completed through the wheels v and the axle v' connecting the rail sections a^2 and a' , upon which current flows through the conductors b , a' , v , v' , v , a^2 , j , k , and c , exciting the electro-magnet e and drawing the armature n into engagement with the contact o . This completes a circuit of the battery B^2 and current flows therefrom through its conductors b^2 , T , s , n , q , R and c^2 , exciting the electro-magnet e^2 . This electro-magnet now draws the armature f^2 into engagement with the contacts g^2 and i^2 . Current now flows through the resistance and signal circuits, from the battery B^2 through the conductors b^2 , d^2 , and f^2 to the contacts g^2 and i^2 , the current dividing here so that part of it returns to the battery by way of the resistance coil h^2 and the electro-magnet e^2 and the remainder by way of the circuit of the signal J, the latter being sounded.

When the train has passed the insulation a , the circuit containing the electro-magnet e is broken and the armature n is released, breaking the circuit of the battery B^2 containing this armature. In this position of the train, the circuit containing the electro-magnet g is closed and the armature k is withdrawn from the contact point d , without however effecting the operation of the signal. The bell continues to ring until the train reaches the track section A' when the signal is discontinued by the connection of the conductors u and u' through the wheels v and axle v' . Current now flows from the battery B^2 through the conductors b^2 , d^2 , f^2 , h^2 , u , v , v' , v , u' and c^2 , cutting out the electro-magnet e^2 and permitting the spring d^3 to withdraw the armature f^2 , which breaks the bell circuit. The train passes the second starting relay without ringing the bell because when the rails a^5 and a^8 are connected current flows from the battery B' through the conductors b' , a^8 , v , v' , v , a^5 , f' and c' , exciting the electro-magnet g' which attracts the armature k' . This withdraws the armature from the contact d' , consequently the circuit containing the electro-magnet e' is broken and the armature n' remains in its normal position, when its circuit is open. When the train has passed the insulation a^4 so as to connect the rail sections a^6 and a^8 , current flows through the conductors b' , v , v' , v , j' , k' , h' , and c' , exciting the electro-magnet g' and holding the armature k' so that the circuit containing the electro-magnet e' remains broken. Hence in passing the second starting relay in this direction, the signal circuit is not closed.

The mechanism shown in Fig. 2 represents a modified construction for cutting out the signal after the lapse of a predetermined period of time. In this construction a conductor c^4 connected with the contact i^2 is wound upon a metal core w contained in a box w' of the same material, the box having a contact w^2 connected by the conductor c^3 with the conductor c^2 and electrically separated by insulation w^3 from the conducting material of the box. A conductor c^5 connects the box w' with the conductor c^2 so as to cut out the electro-magnet e^2 . When, as previously described, current flows back to the battery through the conductor c^2 , exciting the electro-magnet e^2 and drawing the armature f^2 into engagement with the contacts g^2 and i^2 , the signal J is sounded by current flowing through the conductors b^2 , d^2 , f^2 , and i^2 back to the battery by way of the bell circuit. At the same time current flows through the conductor c^4 through the coil around the core w , heating and expanding the latter so that it is brought into engagement with the conductor w^2 . Current now flows by way of the conductors c^5 , w' , w , w^2 , c^3 , and c^2 to the battery, cutting out the electro-magnet e^2 and releasing the armature f^2 , by which the bell circuit is broken.

Having described my invention, I claim:

1. In a signaling mechanism adapted to be operated by a car, in combination with a track for said car, said track comprising several insulated sections, a relay, a signal circuit closed by the armature of said relay when its electro-magnet is excited, a pair of relays connected with different sections of said track for controlling said relay first named, said track sections last named having between them a third section insulated therefrom, each of said pair of relays having a circuit closed by a car moving toward said third section from a track section adjacent the relay whose circuit is thus closed, and means controlled by a car on said third named track section for breaking the circuits of said pair of relays.

2. In a signaling mechanism adapted to be operated by a car, in combination with a track, a pair of relays connected with different sections of said track, the circuits of the respective relays each comprising members electrically connected by a car on said track adjacent the points of connection of said relay thereto, a signal, a relay for controlling the operation of said signal, said last named relay having circuits containing contacts respectively closed by one of said first named relays, and means comprising members electrically connected by a car on said track intermediate of its points of connection with said first named relays for terminating the operation of said signal.

3. In a signaling mechanism, in combination with a track, a pair of circuits each containing a relay magnet and adapted to be closed by a car on said track, a relay 5 having connected therewith circuits respectively controlled by one of said relay magnets, and a signal operated under control of said relay, said relay having means connected therewith whereby the operation of 10 said signal is stopped by said car.
4. In a signaling mechanism, a normally open circuit containing an electro-magnet and an armature, means for closing said circuit, a second normally open circuit containing 15 an electro-magnet adapted for attracting said armature to interrupt said first circuit, said means being adapted for closing said second circuit, in combination with a circuit containing an electro-magnet and an armature adapted to be attracted by said first named electro-magnet, a circuit containing an armature attracted 20 by said last named electro-magnet, and a signal controlled thereby.
5. In a signaling mechanism, a relay having a circuit, a car for closing said circuit, a second circuit, said car closing said second circuit, and means whereby the closing of 25 said second circuit effects the interruption of said first circuit, in combination with a second relay, a plurality of circuits connected with said second relay, said first named relay being adapted for closing one of said circuits connected with said second 30 relay, and the closure of said last named circuit effecting the closure of a second circuit connected with said second relay, a signal, and means whereby the closure of said last named circuit operates said signal.
6. In a signaling mechanism, in combination with a track, a circuit, means operating under control of a car on said track for closing said circuit, a second circuit having means whereby it is closed by said first circuit, a third circuit having means whereby 40 it is closed by said second circuit, a signal operated by closing said third circuit, and 45 means whereby said first and third circuits are broken by said car.
7. In a signaling mechanism, in combination with a track having insulated sections, a circuit comprising an electro-magnet and an armature, conductors connecting the rails of one of said sections with said circuit on either side of said electro-magnet, signaling means, said means being operated when 50 said electro-magnet is excited to attract said armature, a second circuit adapted for exciting said electro-magnet, said last named circuit containing an armature adapted for 55 controlling it, a circuit containing an electro-magnet adapted for operating said second armature, said last named circuit containing an armature and rails of one of said track sections connected by a car, and a third circuit containing an electro-magnet adapted for attracting said last named armature, said last named circuit having a conductor connected with an insulated rail 60 of said last named section and being closed 65 by a car on said track.
8. In a signaling mechanism, a circuit comprising an electro-magnet, a second circuit comprising a resistance coil, an armature adapted to be attracted by said electro-magnet to close said second circuit, a third or signal circuit adapted to be closed by 70 said armature, a fourth circuit adapted to be closed by said armature, said fourth circuit containing a heating coil having a metal core, and a fifth circuit adapted to 75 be opened and closed by the contraction and expansion of said core, said fifth circuit being adapted for cutting out said first named electro-magnet to break said signal 80 circuit.

In witness whereof I have hereunto set my name this tenth day of March, 1910, in the presence of the subscribing witnesses.

JOSEPH W. ROGERS.
